CLAIM

The ornamental design for a display screen or portion thereof with graphical user interface, as shown and described.

DESCRIPTION

The FIGURE is a front view of a display screen or portion thereof with a graphical user interface showing our design. The portions of the graphical user interface showing various forms of stippling represent differing contrasting tones. The broken lines showing a display screen or portion thereof and elements of the graphical user interface illustrate portions of the article, and form no part of the claimed design.
